(57) **ABSTRACT**

The foot spa has a rotating drive hub and a pump. The hub has North and South pole domains encircling a rotation axis in alternating relation. The pump includes a housing and an impeller, the housing having a pair of sides and defining: a cavity having a center and a periphery; an intake that communicates with the cavity center; and one or more ports communicating with the periphery. The impeller is mounted in the cavity and: defines blades which are adapted, upon rotation of the impeller in the cavity, to draw water through the intake and eject water through the one or more ports; and includes a portion that is ferromagnetic and a portion that is not ferromagnetic, the portions: being adapted such that rotation of the drive hub causes rotation of the impeller and abutting one another, one being axially displaced from the other.

1
FOOT SPA WITH DISPOSABLE PUMP

FIELD

The invention relates to the field of pedicures.

BACKGROUND

In the field of esthetics, foot spas are well known. A typical foot spa has a chair, a basin containing water into which the feet of a person seated on the chair can be immersed and a pump for circulating the water.

SUMMARY OF THE INVENTION

Forming one aspect of the invention is a spa. This spa comprises a basin, a motor, a drive hub and a pump.

The basin is for containing water.

The motor is mounted exteriorly of the basin and has a rotating element defining an axis.

The drive hub is disposed exteriorly of the basin and is coupled to the rotating element for movement therewith, the drive hub having magnetic properties such that, in the absence of externalities, a magnetic field is produced which extends from and returns to the hub, the magnetic field being characterized in that, if depicted graphically, concentrations of field lines would appear to extend from one or more North pole domains defined in the surface to one or more South pole domains defined in the surface, the North and South pole domains being spaced apart from each other and arranged to encircle the rotation axis in alternating relation.

The pump includes a housing and an impeller.

The housing is disposed interiorly of the basin and has a pair of sides, one of the pair presenting towards and abutting the basin and the other of the pair opposed in orientation to the one of the pair. The housing defines: a cavity having a center and a periphery; an intake that communicates with the center of the cavity; and one or more ports defined in the other of the pair of sides and communicating with the periphery. The cavity has a generally cylindrical portion

The impeller is mounted in the cavity; defines blades which are adapted, upon rotation of the impeller, to draw water through the intake and eject water through the one or more ports; and includes a portion that is ferromagnetic and a portion that is not ferromagnetic, the portions (i) being adapted such that rotation of the drive hub causes rotation of the impeller and (ii) abutting one another, one being axially displaced from the other.

According to another aspect, the portions can abut one another at a junction that is generally circular.

According to another aspect, the ferromagnetic portion can define the blades.

According to another aspect, the ferromagnetic portion can be steel.

According to another aspect, the ferromagnetic portion can be a steel stamping.

According to another aspect, the portion that is not ferromagnetic can be aluminum.

According to another aspect, the ferromagnetic portion can have a thickness X_{10} , the portion that is not ferromagnetic can have a thickness X_1 , X_{10} can be between about 0.1 mm and 0.2 mm and X_1 can be between about 0.9 mm and 2.0 mm.

According to another aspect, X_{10} can be about 0.15 mm and X_1 can be about 2 mm.

DESCRIPTION OF THE DRAWINGS

FIG. 1 is a view of a spa according to a non-limiting embodiment of the invention, portions shown in phantom for clarity;

FIG. 2 is a partial phantom view of the structure of encircled area 2 of FIG. 1;

FIG. 3A is an exploded view of the structure of FIG. 2;

FIG. 3B is another view of the structure of FIG. 3A;

FIG. 4 is a view of encircled area 4 of FIG. 3B;

FIG. 5 is another view of the structure of FIG. 4;

FIG. 6 is another view of the structure of FIG. 4;

FIG. 7 is an exploded view of the structure of FIG. 4;

FIG. 8 is another view of the structure of FIG. 7;

FIG. 9 is a view along section 9-9 of FIG. 6;

FIG. 9A is a view of detail 9A of FIG. 9;

FIG. 9B is a view of detail 9B of FIG. 9;

FIG. 10 is another view of the structure of FIG. 9;

FIG. 11 is a view of the structure of encircled area 11 of FIG. 7;

FIG. 12 is an exploded view of the structure of FIG. 11;

FIG. 13 is another view of the structure of FIG. 11; and

FIG. 14 is a view along section 14-14 of FIG. 13.

DETAILED DESCRIPTION

Shown in FIG. 1 is a spa 20 comprising a basin body 22 and a motor 24. As seen in FIG. 2, spa further comprises a drive hub 26, a pump 28 and a pump mount 30.

Basin body 22 is constructed of fiberglass and, in combination with pump mount 30, defines a basin for containing a volume of water that is about 35 cm×35 cm×35 cm, which, it will be appreciated, is sufficient to cover the feet of a patron seated for a pedicure. As best seen in FIG. 3B, basin body 22 has an aperture 32 which is occluded in use by pump mount 30.

The motor 24 is a $1/24$ horsepower AC brushless motor disposed exteriorly of the basin and mounted to the motor mount 30 by screws 33 and has a rotating element 34, to wit, a shaft, defining an axis, adapted for rotation between about 2000 and 3000 RPM. The motor rotates at about 3300 RPM when unloaded.

The drive hub 26 is disposed exteriorly of the basin and is coupled to the rotating element for movement therewith, the drive hub having two North Pole domains 36 and two South pole 38 domains arranged to encircle the rotation axis in alternating relation. Each domain is a Neodymium magnet having a mass of about 21 grams and N50 gauss.

As shown in FIGS. 4-14, pump 28 includes a housing 40 and an impeller 42.

The housing 40 is constructed of LDPE plastic, has a total mass of about 33 grams, is disposed interiorly of the basin in use, defines a cavity 44 having a total volume of about 52 ml, a center 46 and a periphery 48, and has a pair of parts 50, 52, each having a thickness T_1 of about 0.80 mm, one 50 of the pair presenting towards and abutting the basin and the other 52 of the pair opposed in orientation to the one of the pair. The center 46 of the cavity is generally round and the periphery includes a pair of lobes 53 that generally encircle the center 46 and expand outwardly in the manner of a nautilus shell.

The one 50 of the pair of parts has a pair of sides and defines:

on one side, a circular recess 54 presenting towards the cavity 44 and having a diameter X_1 of 1.5 mm and a depth X_2 of 3.8 mm

a boss **56** protruding from the base of the recess, the boss having a diameter **X3** of 20.1 mm and a height **X4** of 1.3 mm

a pintle **57** protruding from the boss, the pintle having a height **X5** of 1.0 mm and a diameter **X6** of 6.0 mm on the other of the sides, a plurality of studs **58** presenting in a direction opposite to that of the pintle

The other of the pair of sides defines an intake **60** that communicates with the cavity center **46** and a pair of ports **62** communicating with periphery **48**, the intake **60** having a diameter **X7** of 19 mm and the ports **62** being spaced from one another a distance **X8** of 68.1 mm, the ports **62** being disposed on opposite sides of the intake **60**, each having an area of about 84 cm² and each terminating at the end of a respective lobe **53**. Intake **60** has a plurality of cut-aways **63**.

The impeller includes a portion **64** that is ferromagnetic and a portion **66** that is not ferromagnetic, the portions abutting one another at a junction **68** that is generally circular and being laminated together.

The ferromagnetic portion **64** is constructed from a stamped steel disc of 201 stainless, the disc having a diameter **X9** of 61 mm and a thickness **X10** of 0.15 mm, the stamping being such that five blades **70** project towards the interior of the basin, each being disposed at the edge of the nominal disc, having an area of about 0.12 square inches and being generally triangular in shape, the blades extending out to a diameter **X11** of about 61 mm having a total length **X12** of about 20 mm, a maximum height **X13** of about 6.4 mm, a taper angle α of about 45° degrees and each being disposed at an angle β of about 30° to a radius of the disc.

The portion that is not ferromagnetic is a disc of aluminum having a diameter **X14** of 61 mm and a thickness **X15** of 1.3 mm, such disc being disposed in the recess and having a central hole **72** through which the pintle projects.

The pump mount **30** has a plurality of sockets **74**, each in receipt of one of the studs **58** of the pump **28**, and is configured such that the drive hub **26** is spaced a distance of about 6 mm from the impeller **42**.

In use, when immersed in a mixture of water and sand similar to the mixture in which the feet are immersed in the course of a treatment, the pump produced visible turbulence throughout the basin for about 30 minutes before it failed.

Persons of ordinary skill will readily appreciate that the foregoing is of substantial advantage, in that the product, being constructed out of relatively small amounts of commonplace materials, is relatively inexpensive, thereby to permit hygienic single use only, while at the same time, produces turbulence for a period of time sufficient to conduct a salon treatment of reasonable length.

Whereas a specific embodiment is described, variations are possible, including but not limited to:

materials other than steel, such as T2.5 tin plate or ferroplastic, can be used

materials other than aluminium, such as copper, can be used

the blades need not be stamped

the dimensions can be varied

plastics other than polycarbonate can be used

the number of blades can be varied

the number of ports can be varied

magnets of different strength can be used

the speed of rotation can be varied

the number of magnets can be varied

the distance between the drive hub and the impeller can vary

With specific regard, only, to the thickness of the steel and aluminum discs, utility has been found, in the context of the

drive hub, motor and housing described above, as per the table below. The indications of "low", "medium" and "high" represent the perceived speed of the pump as assessed by visual and auditory observations.

Steel Thickness	Aluminum Thickness		
	.9 mm	1.3 mm	2.0 mm
.10 mm	Speed - low	Speed - medium	Speed - low
.15 mm	Speed - low	Speed - med	Speed - high

As such, the invention should be understood to be limited only by the accompanying claims, purposively construed.

The invention claimed is:

1. A spa comprising:
a basin for containing water;
a motor mounted exteriorly of the basin and having a rotating element defining an axis;
a drive hub disposed exteriorly of the basin and coupled to the rotating element for movement therewith, the drive hub having magnetic properties such that, in the absence of externalities, a magnetic field is produced which extends from and returns to the hub, the magnetic field being characterized in that, if depicted graphically, concentrations of field lines would appear to extend from one or more North pole domains defined in a surface to one or more South pole domains defined in the surface, the North and South pole domains being spaced apart from each other and arranged to encircle the rotation axis in alternating relation;
a pump including a housing and an impeller positioned within the housing, the housing being disposed in an interior of the basin and having a first side and a second side, the first side presenting towards and abutting the basin and the second side opposed in orientation to the first side, the housing defining:

a cavity formed between the first side and the second side having a center and a periphery;
an intake in the second side that communicates with the center of the cavity;
one or more ports defined in the second side and communicating with the periphery;
the impeller defining a plane being mounted in a recess of the cavity, the impeller having a set of angled blades bent from the plane and forming a void in the plane, the set of angled blades that project towards the interior of the basin which are adapted, upon rotation of the impeller in the recess, to draw water through the intake and eject water through the one or more ports;

wherein the impeller includes a first portion that is ferromagnetic and a second portion that is not ferromagnetic, the first and second portions being joined together and adapted such that rotation of the drive hub causes rotation of the impeller via the magnetic field, wherein the impeller and drive hub are axially displaced from one another, wherein the first portion and the second portion of the impeller abut one another at a junction that has a portion that is circular and planar, the first portion of the impeller being disposed entirely to one side of the planar portion of the junction; and wherein the ferromagnetic first portion defines the blades.

2. The spa according to claim 1, wherein the ferromagnetic first portion is steel.

3. The spa according to claim 2, wherein the ferromagnetic first portion is a steel stamping.

4. The spa according to claim 1, wherein the second portion that is not ferromagnetic is aluminum.
5. The spa according to claim 4, wherein the ferromagnetic first portion has a thickness X_{10} , the second portion that is not ferromagnetic has a thickness X_1 , ⁵
 X_{10} is between about 0.1 mm and 0.2 mm, and
 X_1 is between about 0.9 mm and 2.0 mm.
6. The spa according to claim 5, wherein X_{10} is about 0.15 mm and X_1 is about 2 mm. ¹⁰
7. The spa according to claim 1, wherein the intake further comprises a plurality of cut-aways.
8. The spa according to claim 1, wherein there are five blades in the set of angled blades.
9. The spa according to claim 1, wherein each blade in the set of angled blades has an area of about 0.12 square inches. ¹⁵
10. The spa according to claim 9, wherein each blade in the set of angled blades extends out to a diameter X_{11} of about 61 mm having a total length X_{12} of about 20 mm, a maximum height X_{13} of about 6.4 mm, and a taper angle α of about 45°; and ²⁰
wherein each of the blades is disposed at an angle β of about 30° to a radius of the impeller.
